CLAIM

The ornamental design for an interface outlet, as shown and described.

DESCRIPTION

FIG. 1 is a front perspective view of an interface outlet shown in a first position;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

In the drawings, the broken lines are for the purpose of illustrating portions of the interface outlet that form no part of the claimed design. The surface shading is provided for the purpose of illustrating the flat and contoured portions of the device and form no part of the claimed design.
